RAILWAY SIGNALING SYSTEM

Joseph E. Willing, Rochester, and Glenn O. Ferm,
Gates, N. Y., assignors to General Railway Sig-
nal Company, Rochester, N. Y.

Application November 9, 1950, Serial No. 194,842

2 Claims. (Cl. 246—50)

1

This invention relates to multiple block signalling systems, and more particularly pertains to a novel control of the wayside signals over a line circuit.

This invention is to be considered in the nature of an improvement in the line circuit control shown and described in the prior application of Tizzard and Sebeczek, Ser. No. 193,338, filed November 1, 1950; and no claim is intended to be made herein to any subject matter disclosed in such prior application.

In prior conventional three indication block signalling systems, usually a single pair of line wires for each track section can be used to control the signal governing that section by being deenergized while such section is occupied and energized with one polarity when the section in advance is occupied but energized with the opposite polarity when the second section in advance is occupied. These three conditions can then be used to control the signal to give clear, caution or stop indications, depending upon the then existing traffic conditions. However, when the traffic is relatively dense, three indication signalling may require too great a spacing between the trains and it becomes desirable to employ four indication signalling.

In view of the above considerations, it is proposed in accordance with the present invention to provide control for four indication signalling over a single pair of line wires by employing an added condition i. e. apply positive and negative energy alternately at recurring intervals. Such an organization then requires means which is not only distinctively responsive to the different positive or negative line circuit conditions but which is also distinctively responsive to the intermittent energization of the line circuit with opposite polarities alternately.

In accordance with the present invention, it is proposed to provide at each signal two line relays in multiple in such a way that each receives current only of the polarity to which it should respond, and each relay having such a structure as to respond only to its particular polarity. In addition, it is proposed that these relays be so constructed as to have such slow releasing characteristics that both relays will remain picked up when they are intermittently energized with their respective polarities of current.

One of the objects of the present invention might be said to provide an organization as above generally outlined in such a way as to be reliable and protected against static discharges and the like. A further object might be said to be the

2

provision of an improved line circuit electro-responsive means to simplify the signal control under conditions of impulsing.

Other objects, purposes and characteristic features of the present invention will be in part obvious from the accompanying drawing, and in part pointed out as the description of the invention progresses.

In describing the invention in detail, reference will be made to the Figs. 1 and 1A of the accompanying drawings which show the circuit organization associated with a single track section of a multiple block signalling system. The reference characters used in these drawings have been selected to readily convey the relationships between the various devices and the respective signals. Fig. 1A is merely a diagrammatic showing of a polarized relay used in the circuits of Fig. 1.

For the purpose of simplifying the illustration and facilitating in its explanation, the various parts and circuits constituting the embodiment of the invention have been shown diagrammatically and certain conventional illustrations have been employed, the drawing having been made more with the purpose of making it easy to understand the principles and mode of operation, than with the idea of illustrating the specific construction and arrangement of parts that would be employed in practice. The symbols (+) and (—) are employed to indicate the positive and negative terminals respectively of suitable batteries, or other sources of direct current; and the circuits with which these symbols are used always have current flowing in the same direction. If alternating currents were employed, these symbols could be used to represent the relative instantaneous polarities of the alternating current.

Referring to the drawing, a stretch of track has been shown as including the track sections 3T, 4T, and 5T. Each of these track sections, are assumed to have associated therewith the usual conventional track circuits employing a track relay at one end and suitable energy source at the other end. Since the particular characteristics of the track circuits are not involved in the present invention, only the track relay 4TR has been illustrated for the track section 4T.

A signal is shown as located at the entrance to each track section, and these signals may be of any suitable type. However, for convenience in the illustration and description, it is assumed that these signals may be of the searchlight type, such as shown, for example, in the prior patent to O. S. Field, Patent No. 2,376,534, dated May 22, 1945. The signals indicated in the drawing along the

trackway are designated 4 and 5; and these signals are represented by symbols indicating that they are of the three position type. It is of course well understood that the conventional search-light signal, such as disclosed in the above patent, has a movable spectacle carrying three different-colored roundels which are moved to the proper positions to give the desired signal indications. However, it is to be understood that a fourth indication is provided by these signals by causing the incandescent bulb associated with each signal to be intermittently energized to give a flashing indication. Thus, a legend has been placed on the drawing to indicate that a fourth indication is provided by the flashing of the yellow aspect of the signal. In other words, a fourth indication is indicated by legend rather than by the form of the symbols.

Two line wires are provided between each pair of successive signals and these line wires are provided with the different conditions of energization in accordance with traffic conditions and have suitable relay means associated therewith at the entrance end to each track section.

For example, line wires 10 and 11 extend between signals 4 and 5; and line wires 37 and 38 extend between signals 3 and 4 (signal 3 not shown). The line wires 10 and 11 have their energization controlled by contacts of relays 5FY, 5FL and 5GYP at the signal location 5 in addition to control by contacts of the track relay 4TR, which energization of the line wires 10 and 11 selectively actuates the relays 4DR and 4HR at the signal 4. The line wires 37 and 38 have their energization controlled by relays 4FY, 4FL and 4GYP in a similar manner for governing the relays 3DR and 3HR at signal 3 (relays and signal 3 not shown).

More specifically, the line wires 10 and 11 associated with track section 4T have energy supplied thereto in accordance with the condition of relays 5FY and 5GYP together with the operation of a flashing relay 5FL. These relays are of the usual conventional type, while the flashing relay may be of any suitable type such as shown for example in the patent to O. S. Field, Patent No. 1,969,065, dated August 7, 1934. In this connection, it should be understood that such a flashing relay may be replaced by any suitable coder or contactor operating to intermittently open and close circuits at a suitable rate. For the purposes of the present embodiment it is assumed that the flashing relays operate at a rate of 40 to 45 operations per minute.

At the entrance end of the track section two relays 4HR and 4DR are connected in multiple across the line wires 10 and 11 subject to control by contacts 12 and 13 of the associated track relay 4TR. These relays are preferably of the type disclosed in the prior patent to Willing et al., Patent No. 2,502,811, dated April 4, 1950. These relays respond to only one particular polarity, and are so constructed that the application of the opposite polarity will not operate such relays under even the most extreme conditions. Both relays are of course alike, but they are connected to the line circuit so that the relay 4HR will respond to negative energy with respect to the line wire 10, whereas the relay 4DR responds to positive energy with respect to the same line wire 10.

These relays 4DR and 4HR (one of which is typically shown in Fig. 1A) are both provided with two aiding windings 40 and 41, and two

rectifier units R1 and R2 which are respectively connected between the windings of the two relays to allow the flow of current only in the direction to which the respective relays respond. The provision of these rectifiers thus reduces the normal current required on the line circuits and also assists in rendering the relays slow acting for reasons presently to be explained.

Each of these relays is also constructed to have slow releasing characteristics by the provision of the usual "copper slugs," or short circuited windings 43. Assuming the relay structure to be shown in the above mentioned prior patent to Willing et al., the relay structure comprises two core members 44 interconnected at one end by a back yoke 45 and having a cooperating armature 46 adjacent their other ends. Suitable permanent magnets 47 are connected across the core members at their ends adjacent the armature, and a slotted magnetic leakage strip 48 is included in multiple with the permanent magnets to render the relay highly immune to energy of the opposite polarity. The windings of the relay are located on the two core members between the permanent magnets and the back yoke connecting the core members. It is of course to be understood in this connection that the permanent magnet is of such a strength and the back yoke is of such a cross section that it is saturated by flux from the permanent magnet alone all as disclosed and described in detail in the above mentioned patent. Also, the armature is biased away from the core members to a sufficient degree that it will not be actuated by the magnetic flux of the permanent magnets nor will it remain in an actuated position due to such flux from the permanent magnets. In using such a relay in the embodiment of the present invention, copper slugs i. e. short circuited windings 43, are inserted between the permanent magnet and the windings. These copper slugs 43 serve to delay the decay of magnetic flux produced by the windings which passes through the armature to actuate it, all for reasons well understood to those skilled in the art.

Associated with the relays 4HR and 4DR is a conventional neutral relay 4HD controlled by the contacts 14 and 15 of these relays respectively. Thus, the relay 4HD is picked up when either or both of the relays 4HR and 4DR are picked up.

A slow pick up relay 4D is controlled by the relays 4HR and 4DR through contacts 16 and 17 in series. This relay 4D may be made slow to pick up by any of the usual means.

The signal 4 has been diagrammatically illustrated as having an operating mechanism M, contacts 19 and 20, and an incandescent lamp L. The contacts 19 and 20 are shown in their positions when the mechanism M is energized to a green indicating position, and the contact 19 assumes a right hand position when the signal is caused to indicate yellow, whereas, the contact 20 is caused to assume a right hand position when the signal is operated to indicate yellow or is at stop. These contacts 19 and 20 are connected in the usual way to control so-called green-yellow repeater relay 4GYP. This relay 4GYP has a contact 22 which in series with the contact 23 of relay 4DR controls the relay 4FY. This relay 4FY in turn supplies energy through front contact 24 to the flashing relay 4FL. The flashing relay 4FL has been conventionally illustrated as having a self-interrupting contact 25. These relays 4FY and 4FL together

with the slow pick up relay 4D are effective to govern the energization of signal lamp L.

It is to be understood that the relays 5FY, 5GYP, and 5FL associated with the signal 5 are controlled in exactly the same way as the corresponding relays at the signal 4. Thus, it can be understood that each section of the stretch of track has apparatus associated with it similar to that shown for the track section 4T.

It is to be understood that the present invention may be applied to a stretch of track associated with a stretch of automatic signal territory, with a centralized traffic controlling system, or with a stretch of track between interlocking plants where the operators may at their discretion determine when the signals for the stretch of track are to be cleared. For the purpose of the present disclosure it is assumed that the track section shown is in automatic territory, and energy is applied to the line wires extending from the exit end of the stretch, so as to cause the first signal of such strength to give the proper indication, and then each succeeding signal to the rear area is properly controlled in accordance with the traffic conditions. Thus, all of the signals are normally cleared. In any case, the operation of the system is exactly the same upon the passage of a train.

Operation

Let us assume that energy is supplied to the line wires of the last section of the stretch so that all the signals of the stretch are cleared. Under these conditions, the relay 5FY is energized closing its front contacts 26 and 27. This relay 5FY, when energized, causes the flashing relay 5FL to operate, the same as shown for relay 4FL associated with signal 4. Thus, the contacts 28 and 29 of the relay 5FL are alternately picked up and dropped away at some suitable rate, such as 45 times a minute. This causes opposite polarities of energy to be applied alternately through front and back contacts 28 and 29 of relay 5FL and through front contacts 26 and 27 of relay 5FY to the line wires 10 and 11.

It is of course assumed that the track section 4T is unoccupied, so that front contacts 12 and 13 of track relay 4TR are closed. Thus, the pulses of opposite polarity are applied to relays 4HR and 4DR in multiple, but when the upper wire 10 is positive, energy flows only through the relay 4DR by reason of the rectifier R1. Likewise, when the upper wire 10 is negative, energy flows only through the relay 4HR by reason of rectifier R2. Thus, each relay intermittently receives energy of the particular polarity to which it is capable of responding, so that its contacts are picked up and maintained in a picked up position by reason of the slow acting characteristics of that relay.

Since each relay 4HR and 4DR includes a rectifier unit of any suitable type, such as a dry plate copper oxide, or selenium cell type, current flows through the relay only in a direction to pick it up. When the current ceases, the flux can be maintained by the copper slugs to give the desired time delay. Also, the short circuit through the two relays in multiple tends to increase the delay time. This delay or release time is of course long enough to bridge the time between successive energizations of like polarity, so that the relay remains steadily picked up. This not only avoids wear on the relay itself but also obviates the necessity of additional de-

coding means as required in prior systems of this kind.

With both the relays 4HR and 4DR picked up, contacts 14 and 15 both supply energy from (+), to the relay 4HD. Also, the contacts 16 and 17 are both closed so that the circuit to relay 4D is completed. These relays 4HD and 4DP then control the signal 4 to cause it to indicate a green or high speed proceed aspect. More specifically, a circuit is closed for the mechanism M of signal 4 from (+), through a circuit including front contact 30 of relay 4HD, front contact 31 of relay 4D, winding of the mechanism M, and front contact 32 of relay 4D, to (-). With the signal mechanism thus energized, it is operated to a position to give a green indication and the lamp L is energized by reason of the closure of front contact 33 of relay 4DP. In this manner, the signal 4 is caused to give its most favorable proceed indication, which is a green signal light beam.

It should be noted that when the signal 4 indicates green, the relay 4GYP is energized from (+), through a circuit including contact 19 in a left hand position, contact 20 in a left hand position, and windings of relay 4GYP, to (-). This energization of relay 4GYP closes its front contact 22 which completes the circuit for the relay 4FY since under the conditions assumed both relays 4DR and 4HR are steadily picked up. The relay 4FY in turn closes its front contact 24 to supply energy to the flashing relay 4FL which by reason of its self-interrupting contact 25 operates intermittently to open and close its back contact 34. However, at this time the contact 34 is ineffective because the relay 4D is energized.

It is obvious that if a train traveling on the track section 3T should accept the green indication displayed by signal 4 and enter the track section 4T, the track relay 4TR would drop away opening contacts 12 and 13 thus deenergizing the relays 4HR and 4DR. This would result in the deenergization of the mechanism of signal 4, and its operation to its stop position would deenergize the relays 4GYP and 4FY. Thus, the lamp L would be steadily energized by reason of back contact 24 of relay 4FY, regardless of the particular position which the flashing relay 4FL (or other coding mechanism) might assume.

While a train is in a track section in advance of a signal, the apparatus at that signal location causes negative energy to be supplied to the line wires to the next section in the rear. For example, assuming that a train is on the track section 5T, the relays 5FY and 5GYP are both deenergized so that (-) is connected through back contact 35 of relay 5GYP and back contact 26 of relay 5FY to the line wire 10. The return circuit from the line wire 11 is completed through back contact 27 of relay 5FY and back contact 36 of relay 5GYP, to (+). This steady negative energy causes the relay 4HR to be picked up in turn energizing the relay 4HD. But since the relay 4D is deenergized, the energy supplied through the front contact 30 causes the signal mechanism M of signal 4 to be operated to its yellow indicating position. This closes contact 19 in a right hand position and energizes the relay 4GYP. The relay 4FY is not energized since the relay 4DR is deenergized. Thus, back contact 24 supplies steady energy to the lamp L so that the signal 4 can display a yellow indication.

Then the train moves from the track section 5T into the track section 6T beyond signal 6 (not shown), the relay 5GYP is picked up which causes positive potential through front contact 35 from (+) to be applied through back contact 26 to the line wire 10. The return circuit from the line wire 11 is of course completed through back contact 27 and front contact 36. This steady positive energization is supplied to the relays 4HR and 4DR, but only the relay 4DR is energized so that its contacts pick up. The front contact 15 energizes the relay 4HD and the relay 4D remains deenergized. Thus, the signal mechanism M of signal 4 is maintained in its yellow indicating position energizing the relay 4GYP. However, under this situation, the relay 4DR is picked up so that the circuit for relay 4FY is completed through front contacts 22 and 23. This sets the flashing relay 4FL into operation, and with the back contact 24 open energy for lamp L is intermittently supplied through back contact 33 of relay 4D and back contact 34 of the flashing relay 4FL. This contact 34 of the flashing relay is intermittently opened and closed so as to cause the lamp L to flash and thus cause the signal 4 to display a less restrictive proceed indication. In this connection, it might be noted that the flashing yellow indication is used as a less restrictive indication than a steady yellow so as to provide an arrangement organized on the side of safety. For example, should the front contact 24 fail, or should the flashing relay 4FL cease its operation, then the back contact 34 would be closed and the lamp L steadily energized. In other words, a failure of the flashing equipment causes a steady yellow indication to be given. Since this is considered to be more restrictive, such a failure would be entirely safe.

When the train moves out of the track section 6T into the track section 7T beyond signal 7 (not shown), the conditions are repeated so that at signal 5 the relay 5FY is picked up which causes operation of the flashing relay 5FL and thus causes the line wires 10 and 11 to be alternately energized with opposite polarities at the selected rate. This causes the signal 4 to be controlled to give its green proceed indication, as previously described.

Having thus described the control of the block signalling system as one specific embodiment of the present invention, it is desired to be understood that this particular form is selected to facilitate in the disclosure of the invention rather than to limit the number of forms which it may assume; and, it is to be further understood that various modifications, adaptions and alterations may be applied to the specific form shown to meet the requirement of practice, without in any manner departing from the spirit or scope of the present invention.

What we claim is:

1. In combination, a section of railway track, a signal for governing traffic over said section,

two conductors extending from said signal location to the other end of said section at which energy is applied to said conductors in accordance with traffic conditions, one polarity being applied when the next section in advance is occupied, the opposite polarity being applied when the second section in advance is occupied and both polarities being alternately applied at intervals when the third section in advance is occupied, two signal control relays at said signal location connected in multiple across said conductors each having a rectifier included in series with its windings, said rectifiers being oppositely connected to permit the energization of only one relay in response to either polarity of energization of said conductors, and each of said relays having slow acting structural characteristics, one of said relays having a permanent magnet associated therewith to render it responsive to only a particular polarity and the other having a permanent magnet associated therewith for rendering it responsive to only the opposite polarity, said relays both being steadily actuated in response to the intermittent alternate application of both polarities, and signal control circuits governed by said relays for causing said signal to give different proceed indications dependent upon whether one or the other or both of said signal control relays are actuated.

2. In combination with a circuit having current of either polarity applied thereto and at times pulses of opposite polarities alternately, two polarized relays connected in multiple to said circuit so as to respectively respond to opposite polarities, each of said polarized relays having a permanent magnet connected across its core members adjacent its armature to render that relay responsive to energization of only one particular polarity, short circuited windings surrounding its core members adjacent said permanent magnet to render the armature of that relay slow in releasing, a rectifier unit connected in series with each of said relays to allow current flow in a direction through its respective relay corresponding to the direction of current flow to which that relay will respond, whereby said relays selectively respond to the polarity of energy on said circuit and both of said relays remain steadily operated when said circuit is energized with pulses of opposite polarity alternately.

JOSEPH E. WILLING.
